UNITED STATES PATENT OFFICE

2,365,767

APPARATUS FOR BLEACHING FLOUR

Hugh McDonald, Minneapolis, Minn., assignor to
Pillsbury Flour Mills Company, Minneapolis,
Minn., a corporation of Delaware

Original application May 3, 1941, Serial No.
391,735. Divided and this application September
21, 1942, Serial No. 459,109

4 Claims. (Cl. 99—263)

This invention relates to apparatus for bleaching flour and other analogous powdered material.

This application is a division of my United States application for patent entitled "Process for bleaching flour," Serial No. 391,735, filed May 3, 1941, now Patent No. 2,307,631, issued January 5, 1943.

It is a common practice at the present time in the flour industry to bleach flour by subjecting the same to the action of a bleaching gas such as chlorine gas. As the bleaching process is at present carried out there is an opportunity for the flour to lodge on the walls of the bleaching apparatus causing over-treatment of the lodged flour, necessitating frequent clean out of the bleaching apparatus and also often causing admission of over-treated lumps of flour in the flour stream.

It is an object of the present invention to provide a novel and improved apparatus for bleaching flour wherein a gaseous bleaching medium is used, the apparatus being so constructed as to thoroughly and intimately bring the bleaching gas into contact with the fine particles of the flour to produce a uniform and thorough bleaching action with neither over-treatment nor under-treatment.

Another object is to provide a novel and improved bleaching apparatus for flour which can be operated continuously without shut down periods and without the necessity for cleaning out the apparatus and which will eliminate the possibility of lumps of over bleached flour passing to the flour stream from the bleaching apparatus.

The objects and advantages of the present invention will more fully appear from the following description made in connection with the accompanying drawings, wherein like reference characters refer to the same or similar parts throughout the various views, and in which—

Fig. 1 is a view in front elevation of an apparatus made in accordance with the present invention;

Fig. 2 is a view in side elevation of the same apparatus;

Fig. 3 is a plan view of the said apparatus;

Fig. 4 is a horizontal section taken on the line 4—4 of Fig. 1 as indicated by the arrows;

Fig. 5 is a vertical section taken on enlarged scale on the line 5—5 of Fig. 2 as indicated by the arrow; and

Fig. 6 is a detail in still larger scale illustrating the rotating dish in vertical section and show-

ing the lower adjacent part of the feed spout in dotted lines.

Referring to the drawings, a typical apparatus made in accordance with the present invention is shown. This bleaching machine includes a large drum designated as an entirety by the letter "A" and having an upper cylindrical portion 6 closed at its upper end by a cover plate 7. The lower end of the cylindrical portion 6 of the drum is connected to two dividing trunks 8 each of which has outer half conical walls 8a and inner walls 8b which extend downwardly from a transverse medial line running fore and aft of the drum "A" at the lower part of the cylindrical portion 6 and which walls 8b are also curved in horizontal cross section and taper from their upper edges to their lower edges. The walls of the dividing trunks 8 are quite steep so as to prevent the lodging of flour thereon. At their lower ends the dividing trunks are of elliptic shape as shown in Fig. 4 and they join collecting trunks 9 at their lower ends which collecting trunks run down diagonally toward each other to join and form an outlet mouth 10. This mouth 10

25 delivers into a horizontally disposed cylindrical conveyor casing 11 which runs to one side of the drum "A" and is in turn equipped with an outlet 12. The central portions of the walls 8b of the dividing trunks are not joined and a box-

30 like bearing bracket 13 joins these walls at this point for a purpose presently to be described.

A flour chute 14 for feeding flour into the drum "A" is mounted centrally in the cover plate 7 and projects downwardly into the cylindrical portion 6 of the drum "A." This chute 14 is preferably provided at its lower end with a telescoping chute extension 14a whereby the level of the lower end of the chute is capable of adjustment. A bracket 15 is secured to the two walls 8b below the box-like bracket 13 and the bracket 13 carries on its upper side a thrust bearing 16 within which an upwardly extending vertical shaft 17 is journaled. This shaft 17 is also journaled in a bearing 18 secured to the underside of the top of the box-like bracket 13.

The shaft is packed by packing 19 at the point where it emerges from the box-like bracket 13 and the shaft extends upwardly to a point adjacent to but spaced slightly below the lower edge of the extension 14a of the chute 14.

At its upper end the shaft 17 carries a shallow rotating dish 20 which is provided with serrations or teeth 21 at its upper edge as best shown in Fig. 6. The lower end of the chute extension 14a extends into the dish 20 to a point adjacent

to but spaced upwardly somewhat from the bottom of the dish.

Secured to the shaft 17 below the dish 20 is a large fan 22 the blades of which are pitched relative to the direction of rotation of the shaft 17 so that the fan will force a blast upwardly from below the dish 20. A pair of gas pipes 23 for the admission of bleaching gas are mounted in the top plate 7 of the drum and these pipes are supplied with the bleaching gas from any suitable source of supply as through hoses 24. Gases that may be employed for the purpose are chlorine, nitrogen trichloride, oxides of nitrogen etc. and it is contemplated that one or a mixture of such gases will be used in connection with the present machine.

In order to suitably support the drum "A" a stand consisting of four legs 25, side cross bars 26 and front and rear cross bars 27 is provided, said legs being attached by suitable brackets 28 to the dividing trunks 8 of the drum "A." At the front of the machine a driving shaft 29 is provided and this shaft is journaled in suitable bearings 30 carried by the two front legs 25. This shaft is adapted to be driven as by a belt (not illustrated) from any suitable source of power and the belt will run over a pulley 31 carried by the shaft 29 at one end thereof. The shaft 29 is located adjacent the lower end of the shaft 17 and the shaft 29 carries a vertical pulley 32 over which a belt 33 travels, this belt also running over a horizontal pulley 34 carried by the shaft 17 between the walls 35 adjacent the lower end of the shaft.

Journaled in a bearing 35 carried by the side bars 26 and also journaled in suitable bearings 36 carried at the ends of the conveyor casing 11 is a horizontal conveyor shaft 37 which extends from the left side of the machine as shown in Fig. 5 through the conveyor casing 11. This shaft is driven from the left end of the shaft 29 as viewed in Fig. 1 by means of a pulley 38 carried by the shaft 29, a pulley 39 carried by the shaft 27 in alignment with the pulley 38 and an endless belt 40 running over the two pulleys 38 and 39. Within the conveyor casing 11 the conveyor shaft 37 carries a plurality of pitched vanes 41 and the direction of rotation of the shaft 37 is such relative to the pitch of the vanes 41 that these vanes will work the flour from the mouth 10 to the mouth 12. Extending into the conveyor casing 11 from the mouth 10 is a partition 42 which runs downwardly across the upper portion of the casing to a point about midway between the top and bottom thereof and between a pair of the vanes 41, the said partition being notched to receive the conveyor shaft 37. Another partition 43 runs down in similar manner adjacent to but spaced to the left of the outlet 12 as viewed in Fig. 5.

When the bleaching machine is in operation the bleaching gas is delivered into the drum "A" from the pipes 23 preferably into the upper part of the drum. Flour is delivered through the chute and its extension 14a on to the dish 20. The dish 20 rotates at high speed and as the flour is received by the dish it is thrown off centrifugally by the dish and the serrated teeth 21 act in throwing off the flour to break it up and divide it. The fan 22 working below the dish 20 throws up a blast into the flour thrown out centrifugally by the dish 20 and this blast further divides the flour into a fine shower or dust cloud wherein the individual flour particles are spaced one from

another in detached relation to bring the bleaching gas introduced into the top of the drum into intimate contact with the individual flour particles, whereby the flour is rapidly bleached. The bleached flour falls into the dividing trunks 8 and is then collected by the collecting trunks 9 to discharge from the mouth 10 into the conveyor casing 11. The conveyor, consisting of the shaft 37 and the vanes 41, is rotated at such speed relative to the quantity of flour delivered thereto that the flour in the casing 11 will always more than half fill the conveyor casing 11 and accordingly the partition 42 will seal off the drum "A" at its lower end so that the bleaching gas cannot escape through the conveyor casing 11. To be doubly sure of sealing off the lower end of the drum "A" a secondary partition 43 is provided. The flour working into the casing 11 is moved by the vanes 41 to the right, as viewed in Fig. 5, and discharged through the outlet mouth 12.

With the arrangement shown the flour is broken up into a fine shower with the individual particles in detached relation and acted on by bleaching gas and it delivers out of the drum "A" without in any way clinging to the drum. By reason of the fact that the flour cannot cling to the drum it cannot build up thereon to be over-treated by the bleaching gas and to require frequent clean out of the drum. Also by reason of the fact that the flour cannot build up in the drum "A" lumps of over-bleached flour cannot fall off to enter the discharged flour stream. The breaking up of the flour into individual separate particles by means of the air blast permits proper uniform bleaching of all the parts of the flour with the minimum quantity of bleaching gas and without over-treatment or under-treatment of any part of the flour.

For certain types of flour it may be desirable to vary the spacing of the lower end of the chute 14 relative to the dish 20 and for this purpose the extension 14a of the chute is made adjustable upwardly and downwardly relative to the main part of the chute.

It will be seen that a highly efficient bleaching machine has been provided. Various changes may be made in the form, details, arrangement and proportions of the various parts of the bleaching machine without departing from the scope of the invention which generally stated consists in the matter shown and described and set forth in the appended claims.

What is claimed is:

1. A machine for bleaching flour comprising a closed upright drum having means for collecting and removing the treated flour from the lower portion thereof, means for continuously discharging flour from the central portion of said drum and at a level some distance below the top of said drum, a centrifugal rotary distributor of slightly greater area than the cross sectional area of said discharge means mounted below said flour discharge means and receiving therefrom and constructed to cause the flour to be finely divided and thrown out centrifugally and somewhat upwardly therefrom, means for discharging a bleaching gas within said drum and a fan disposed some distance below both of said distributor and said gas discharge and of several times the diameter of said distributor for directing a blast upwardly into the distributed flour and into and against the bleaching gas introduced.
2. A flour bleaching machine comprising a

closed upright drum, means for discharging a bleaching gas within said drum, a flour delivering medium having a downwardly directed discharge disposed substantially axially within said drum at some distance below the top of said drum, a centrifugal, rotary distributor mounted axially a short distance below said discharge and constructed to finely divide and throw out centrifugally and somewhat upwardly a shower of flour particles in the upper portion of said drum, said distributor having an area somewhat greater than the cross sectional area of said discharge but relatively very small to the cross sectional area of said drum, a fan independent of said distributor but mounted co-axially thereof in spaced relation some distance below said distributor and having a diameter several times the diameter of said distributor and constructed to set up from below said distributor an upwardly moving current of air into the shower of finely divided flour in the upper portion of said drum, means for driving said fan and said distributor and means at the lower end of said casing for removing the treated flour therefrom.

3. A flour bleaching machine comprising a closed upright drum, means in the upper portion of said drum for discharging a bleaching gas within said drum, a flour delivering medium having a downwardly directed discharge disposed substantially axially within said drum at some distance below the top of said drum, a centrifugal, rotary distributor in the form of a shallow dish mounted axially a short distance below said discharge and constructed to finely divide and throw out centrifugally and somewhat upwardly a shower of flour particles in the upper portion of said drum, said distributor having an area somewhat greater than the cross sectional area of said discharge but relatively very small to the cross sectional area of said drum, a fan independent of said distributor but mounted co-

axially thereof in spaced relation some distance below said distributor and having a diameter several times the diameter of said distributor and constructed to set up from below said distributor an upwardly moving current of air into the shower of finely divided flour in the upper portion of said drum, means for driving said fan and said distributor and means at the lower end of said casing for removing the treated flour therefrom.

4. A flour bleaching machine comprising a closed upright drum, means for discharging a bleaching gas within said drum, a flour delivering medium having a downwardly directed discharge disposed substantially axially within said drum at some distance below the top of said drum, a centrifugal, rotary distributor mounted axially a short distance below said discharge and constructed to finely divide and throw out centrifugally and somewhat upwardly a shower of flour particles in the upper portion of said drum, said distributor having an area somewhat greater than the cross sectional area of said discharge but relatively very small to the cross sectional area of said drum, a fan independent of said distributor but mounted co-axially thereof in spaced relation some distance below said distributor and having a diameter several times the diameter of said distributor and constructed to set up from below said distributor an upwardly moving current of air into the shower of finely divided flour in the upper portion of said drum, means for driving said fan and said distributor, means at the lower end of said casing for removing the treated flour therefrom, the lower portion of said drum being constructed in the form of two downwardly extending trunks disposed below said fan and means at the lower ends of said trunks for removing the treated flour therefrom.

HUGH McDONALD.
